[57] ABSTRACT

In a low-frequency power amplifier designed for Class B or AB operation which comprises a first complementary pair of transistors connected in the form of Darlington connection, and a second complementary pair of transistors connected in the form of Darlington connection, there is provided means for permitting a bias current to flow through said transistors, whether or not there is an input signal, thereby preventing notching distortion.

FIG. 1

FIG. 2

LOW-FREQUENCY POWER AMPLIFIER

This invention relates to improvements in low-frequency power amplifier circuits.

Most of the low-frequency power transistor amplifiers which have extensively been used heretofore, are single-ended push-pull (referred to as SEPP hereinafter) circuits, especially complementary SEPP circuits using complementary pairs of transistors connected in the form of Darlington connection. Such circuits are commonly designed for class B or AB push-pull operation which is advantageous in respect of power source capacity, collector loss, type of heat dissipating means, etc. With such circuit arrangements, however, there inevitably occur crossover distortion, notching distortion and so forth. Crossover distortion can be prevented by flowing a high bias current through each transistor, whereas notching distortion cannot be avoided unless an arrangement for class A operation is adopted, since such distortion is one which results from switching of the transistors. Obviously, class A operation is disadvantageous in that it is accompanied by much greater power loss.

Accordingly, it is a primary object of this invention to provide a low-frequency power amplifier circuit arrangement which is designed for class B or AB operation and yet free from not only crossover distortion but also notching distortion.

According to an aspect of this invention, there is provided a low-frequency power amplifier circuit arrangement designed for Class B or AB operation, comprising a first transistor of a first conductivity type, a second transistor of a second conductivity type having the base thereof connected with the collector of said first transistor, a first diode having the positive and negative electrodes thereof connected to the emitter of said first transistor and the collector of said second transistor respectively, a third transistor of said second conductivity type, a fourth transistor of said first conductivity type having the base thereof connected with the collector of said third transistor, a second diode having the negative and positive electrodes thereof connected to the emitter of said third transistor and the collector of said fourth transistor respectively, a resistor connected between the emitters of said first and third transistors, and a bias circuit means connected between the bases of said first and third transistors, the collectors of said second and fourth transistors being connected to a load.

Other objects, features and advantages of this invention will become apparent from the following description taken in conjunction with the accompanying drawings, in which:

FIG. 1 is a schematic circuit diagram showing the low-frequency power amplifier according to an embodiment of this invention; and

FIG. 2 is a view useful for explaining the operation of the amplifier shown in FIG. 1.

Referring to FIG. 1, a differential amplifier 4 is provided which comprises a pair of PNP transistors T_1 and T_2 the emitters of which are coupled to each other and to a power source terminal 1 through a resistor 5. The collector of the transistor T_2 is coupled direct to another power source terminal 2 to which is also coupled the collector of the transistor T_1 through a resistor 6. To the base of the transistor T_1 are connected a capacitor 7 the other end of which constitutes an input terminal 8, and a resistor 9 which is grounded at the other

end. The base of the transistor T_2 is connected to a load R_L through a resistor 10 and also grounded through a series circuit of a capacitor 11 and resistor 12.

An NPN transistor T_3 serves as a power driver with 5 the base thereof coupled to the collector of the transistor T_1 and with the emitter thereof coupled to the power source terminal 2.

An NPN transistor Q_1 has its base connected to the collector of the power driver transistor T_3 through a 10 bias circuit 3 and also to the power source terminal 1 through a constant current source 13. A PNP transistor Q_2 has its base connected to the collector of the NPN transistor Q_1 which is coupled to the power source terminal 1 through a resistor R_4 . The emitter of the PNP transistor Q_2 is coupled to the power source terminal 1, 15 and the collector thereof is coupled to the load R_L through a resistor R_1 . A diode D_1 is provided which has its positive and negative electrodes connected to the emitter of the NPN transistor Q_1 and the collector of the PNP transistor Q_2 respectively.

A PNP transistor Q_3 has its base connected direct to the collector of the power driver transistor T_3 , and an NPN transistor Q_4 has its base connected direct to the collector of the PNP transistor Q_3 which is also coupled 25 to the power source terminal 2 through a resistor R_5 . The emitter of the NPN transistor Q_4 is connected to the power source terminal 2, and the collector thereof is coupled to the load R_L through a resistor R_2 . A second diode D_2 is provided which has its positive and negative electrodes connected to the collector of the NPN transistor Q_4 and the emitter of the PNP transistor Q_3 respectively.

Between the emitters of the transistors Q_1 and Q_3 is connected a resistor R_3 , the function of which will be 35 fully described later.

Description will now be made of the operation of the circuit shown in FIG. 1. When no signal is being applied to the input terminal 8, it is assumed that the voltages between the bases and the emitters of the transistors Q_1 and Q_3 and V_{BE1} and V_{BE3} respectively, that the forward voltage drops across the diodes D_1 and D_2 are V_{D1} and V_{D2} respectively, that the voltages across the resistor R_3 40 and the voltage across the bias circuit 3 is V_b , as shown in FIG. 2. In this case, the values of the resistors R_1 and R_2 are so small and the current flowing through the transistors Q_2 and Q_4 are so low that the voltage drops across these resistors can be neglected. Thus, it will readily be understood that the following 45 equation holds:

$$V_b - V_{BE1} - V_{BE3} = V_R = V_{D1} + V_{D2}$$

When an input signal is applied to the input terminal 8, and during each positive half cycle thereof, it is assumed that a current I is caused to flow through the load L_R as shown in FIG. 2. It is further assumed that the load current I is much greater than the bias current, and that the voltage variations at the operating points of the transistors Q_1 and Q_2 are $+ \alpha$ and $- \beta$ respectively. Then, the foregoing equation can be rewritten as 55 follows:

$$\begin{aligned} & V_b - (V_{BE1} + \alpha) - (V_{BE3} - \beta) \\ & = V_b - V_{BE1} - V_{BE3} - (\alpha - \beta) \\ & = V_R - (\alpha - \beta) \quad [\text{Usually, } V_R > (\alpha - \beta)] \end{aligned}$$

Normally, the voltage drop across the resistor R_1 due to the increase in the collector current is greater than the variations in the base-emitter voltage. Hence, the 60 following relationships hold true:

$$(\alpha - \beta) < I.R_1$$

$$V_R - (\alpha - \beta) < (V_{D1} + V_{D2} + I.R_2)$$

In this case, the diode D_1 is rendered conductive by the fact that the emitter current of the transistor Q_1 flows therethrough, whereas the diode D_2 is rendered non-conductive by the fact that the voltage thereacross does not reach the level of the forward bias voltage thereof. Furthermore, the variation in the voltage across the resistor R_3 is small, and the current flowing therethrough is caused to flow through the transistor Q_3 as emitter current, so that the variation in the latter is also small. In this way, since the variation in the emitter current of the transistor Q_3 is small, the variation in the voltage drop across the resistor R_5 is also small, so that the transistor Q_4 is still conducting. Thus, during each positive half cycle of the input signal, both the transistors Q_3 and Q_4 are conducting so that the signal is subject to no notching distortion. During each negative half cycle of the input signal, the diode D_1 is rendered non-conductive, so that the transistors Q_1 and Q_2 are kept conductive by being supplied with the bias current, as will be readily apparent to those skilled in the art from what has been described above.

In order to keep the transistors Q_2 and Q_4 supplied with the bias current, the values for the resistors R_4 and R_5 for shunting the collector currents of the transistors Q_1 and Q_3 respectively, should preferably be selected to be sufficiently greater than the input impedances between the bases and the emitters of the transistors Q_2 and Q_4 so as to achieve constant-current driving.

As will be understood from the foregoing, according to this invention, the bias current flowing through the first transistor Q_1 will always be permitted to flow into the emitter of the transistor Q_3 via the resistor R_3 , whether or not there is an input signal; The current increased by the input signal will be passed to the load through one of the diodes, and the voltage across the resistor R_3 will be prevented from changing by the other diode, so that the first and third transistors Q_1 and Q_3 will always be conducting. Thus, even when the operating point is set up to give Class B or similar operation, notching distortion can be avoided which results from switching of transistors. The same effect can be

produced even when the resistors R_1 and R_2 are eliminated. Such resistors may be provided between the emitters of the second and fourth transistors Q_2 and Q_4 and the power source. In order to make the operation more effective, the bias circuit 3 should preferably be one which provides a constant voltage irrespective of input signals.

While the present invention has been described with respect to specific embodiments thereof, it should be understood that the invention is not restricted to those embodiments but various modifications may be made therein without departing from the spirit and scope of the invention as defined in the appended claims.

What is claimed is:

1. A low-frequency amplifier circuit arrangement designed for Class "B" or "AB" operation, comprising: a first amplifier stage including a first transistor of a first conductivity-type and a second transistor of a second conductivity-type having the base thereof connected with the collector of said first transistor; a second amplifier stage including a third transistor of said second conductivity-type and a fourth transistor of said first conductivity-type having the base thereof connected with the collector of said third transistor; said second and fourth transistors having the collectors thereof connected to a load to alternately drive said load; and means for preventing said first and third transistors from being brought into cut-off condition, regardless of whether one of said second and fourth transistors are driving said load; said means comprising bias circuit means connected between the bases of said first and third transistors, a non-grounded resistor through which the emitters of said first and third transistors are connected to each other, a first diode having the anode and cathode thereof connected to the emitter of said first transistor and the collector of said second transistor respectively, and a second diode having the anode and cathode thereof connected to the collector of said fourth transistor and the emitter of said third transistor respectively.
